UNITED STATES PATENT OFFICE.

JAMES A. PLANT, OF HARTFORD, CONNECTICUT.

DESIGN FOR A TOY.

36,471.

Specification for Design.

Patented Oct. 26, 1920.

Application filed January 6, 1919. Serial No. 269,930. Term of patent 7 years.

To all whom it may concern:

Be it known that I, JAMES A. PLANT, a citizen of the United States, residing at Hartford, in the county of Hartford and State of Connecticut, have invented a new, original, and ornamental Design for Toys, of which the following is a specification,

reference being had to the accompanying drawings, forming part hereof, in which—

The figure is a perspective view of a toy embodying my improved design.

I claim:—

The ornamental design for a toy as shown.
JAMES A. PLANT.
